CLAIM

The ornamental design for a knee protector for motorcyclist's coveralls, as shown and described.

DESCRIPTION

FIG. 1 is a top plan view of knee protector for motorcyclist's coveralls showing my new design;

FIG. 2 is a bottom plan view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a rear perspective view thereof and,

FIG. 8 is a front perspective view shown in use, the broken line showing of a coverall is for illustrative purposes only and forms no part of the claimed design.

FIG. 1

FIG.2
